UNITED STATES PATENT OFFICE.

HARRY SWINGLEHURST, OF BOSTON, MASSACHUSETTS, ASSIGNOR TO SCOTT & WILLIAMS, INCORPORATED, OF CAMDEN, NEW JERSEY, A CORPORATION OF NEW JERSEY.

LATCH-NEEDLE FOR KNITTING-MACHINES.

1,168,039.

Specification of Letters Patent Patented Jan. 11, 1916.

Application filed February 14, 1911. Serial No. 2,152,121.

To all whom it may concern:

Be it known that I, HARRY SWINGLEHURST, a citizen of the United States, residing in Boston, Massachusetts, have invented certain improvements in Latch-Needles for Knitting-Machines, of which the following is a specification.

The object of my invention is to so construct a latch needle for knitting machines as to permit the upper end of the needle and its closed latch to be drawn through the stitch with less strain upon or distention of said stitch than is caused when the needle is constructed in the usual manner. This object I attain in the manner hereinafter set forth, reference being had to the accompanying drawing, in which—

Figure 1 is a side view, on an enlarged scale, of the upper portion of a knitting machine latch needle of the usual type, and Fig. 2 is a similar view illustrating a needle constructed in accordance with my invention.

In the drawing, 1 represents the upper portion of the needle stem or shank, 2 the hook at the upper end of the same, and 3 the swinging latch which closes against the point of the hook when the needle is drawn down through the old stitch, the latter slipping over the latch and hook, or, as it is termed "knocking over" as the new stitch is drawn down through the same.

In a needle of the usual type, there is a gradual distention of the stitch from the time the base of the latch enters the same until the stitch is slipped over the hook, and not only is the stitch thereby strained but the power required to retract the needle gradually increases during this portion of its movement. I find that this disadvantage of the ordinary latch needle can be overcome by imparting a forward inclination to the rear face of the upper portion of the needle stem or shank, such inclination extending from the base of the latch to the hook, as shown for instance, at 4 in Fig. 2, the angle presented by this portion of the back of the

needle stem, by preference, approximating that presented by the outer face of the closed latch, so that the width across the upper end of the latch and across the hook is but little, if any greater, than that of the needle shank at the pivotal point of the latch. The forward inclination of the upper portion of the needle stem or shank permits of the formation of a small hook and yet locates the point of the hook in substantially the same plane as that of the larger hook of the ordinary needle, and thereby insures the engagement of the knitting yarn with the hook in the ordinary operation of the machine.

I am aware that latch needles have been provided with forwardly inclined and hooked upper portions, but no such prior needle of which I am aware has presented such relation between the inclined back of the needle stem and the forward face of the latch as to prevent distention and strain upon the stitch during any portion of the travel of the latch through the same.

I claim:

A knitting machine latch needle having at its upper end a hook, and a pivoted latch whose free end engages the front portion of said hook, the back of the needle being inclined forwardly from the pivot of the latch to the hook so as to contract the latter, and said inclined back of the needle being substantially parallel with the outer face of the latch when the latter is closed against the hook, the distance around the needle and latch at any point along the inclined back of the needle being substantially the same as the distance around the shank of the needle at the pivot point of the latch.

In testimony whereof, I have signed my name to this specification in the presence of two subscribing witnesses.

HARRY SWINGLEHURST.
